FIG.2

INVENTOR.

JOEL M. CADWELL.

BY *G E Hamaker*
ATTORNEY.

UNITED STATES PATENT OFFICE.

JOEL M. CADWELL, OF PORTLAND, OREGON.

FOLDING TABLE.

1,413,706.

Specification of Letters Patent. Patented Apr. 25, 1922.

Application filed March 21, 1921. Serial No. 453,949.

To all whom it may concern:

Be it hereby known that I, JOEL M. CADWELL, a citizen of the United States, and resident of Portland, in the county of Multnomah and State of Oregon, have invented a new and useful Folding Table, of which the following is a specification.

This invention relates more particularly to collapsible tables.

10 The objects of my invention are chiefly to provide a table which can be readily folded into a very small bundle and which, when set up for use, provides an exceedingly light and substantial table without taking up the 15 space underneath.

I attain these results in the manner set forth in the following specification and illustrated in the accompanying drawing, in which:

20 Figure 1 is an end elevation of an erected table of which Figure 2 is a side elevation and Figure 3 a plan. Figure 4 is a side elevation showing the table partly folded and Figure 5 is a sectional elevation showing it entirely folded.

Similar numbers of reference refer to the same or similar parts throughout the several views.

Referring in detail to the drawing, I 30 have constructed my device of the boards 7, 8, 9, 10 and 11 which are joined by the hinges 12 on their under sides. On the under side of the central board 9 I have secured the aprons 13, to the under side of 35 which are hinged the slotted vertical legs 14 by means of the hinges 15. Between the aprons 13 I have placed a longitudinal brace 16, on the opposite sides of which are placed the wood screws 17. Diagonal braces 18 40 are provided with hooks 19 at their upper ends which can engage the screws 17. The braces 18 are pivoted at their lower ends between the slots in the legs 14.

At either end of the table I have provided 45 a pair of removable crossed legs 20 whose upper ends are provided with bent metal tips 21 which are adapted to slip into the straps 22 on the under sides of the boards 7 and 11. A bolt 23 and wing nut 24 are

used to clamp the members 20 and 14 together.

It is intended that minor details of my device can be varied considerably without departing from the spirit of my invention.

It can be seen in Figures 4 and 5 that the table adapts itself to exceedingly compact folding and that from the arrangement of its parts is developed a table which has surprising rigidity in proportion to its weight.

60 What I claim as new is:

1. A table having a top consisting of five boards hinged on their under sides, the central board member having hinged to its under side near its ends a pair of vertical leg members, and a pair of crossed legs engaging and supporting the outer board members and joined at their intersections to said vertical legs and adapted to fold into box form as long and as wide as said boards. 65

2. A table having a top consisting of five boards hinged on their under sides, the central board member having hinged to its under side near its ends a pair of vertical leg members resting on the floor and having 70 brace hooks adapted to engage the under side of the table, and a pair of crossed legs engaging and supporting the outer board members and joined at their intersections to said vertical legs and adapted to fold into 75 box form whose sides are formed by said boards.

3. A table having a top consisting of five board members hinged together on their under sides, the central board member having secured near its under end a pair of apron members separated by a brace secured to the under side of said central member, a pair of slotted vertical leg members hinged to said aprons whose feet rest on the floor, a pair of crossed legs removably joined to the ends of said outer board members and said vertical leg members, a bolt member 85 for securing said crossed legs to said slotted legs, and hook braces between said vertical 90 legs and said apron members.

JOEL M. CADWELL.
